UNITED STATES PATENT OFFICE.

JULIUS HOROWITZ, OF NEW YORK, N. Y., ASSIGNOR TO EAGLE LITES, INC., A CORPORATION OF NEW YORK.

DESIGN FOR A LIGHTING-FIXTURE PART OR ANALOGOUS ARTICLE.

Application filed August 13, 1927. Serial No. 23,079. Term of patent 3½ years.

To all whom it may concern:

Be it known that I, JULIUS HOROWITZ, a citizen of the United States, and a resident of New York, county of Bronx, and State of New York, have invented a new, original, and ornamental Design for a Lighting-Fixture Part or Analogous Article, of which the following is a specification, reference being had to the accompanying drawing, forming a part hereof.

In the drawings:

Figure 1 is a front elevational view of the lighting fixture part or analogous article; and

Figure 2 is a diagrammatic top view of the same.

I claim:

The ornamental design for a lighting fixture part or analogous article substantially as shown.

JULIUS HOROWITZ.
